UNITED STATES PATENT OFFICE.

JOHN DESMOND, OF CHICAGO, ILLINOIS, ASSIGNOR TO WILLIAM S. POTWIN, OF CHICAGO, ILLINOIS.

COMPRESSION-TESTER FOR EXPLOSIVE-ENGINES.

946,661.

Specification of Letters Patent. Patented Jan. 18, 1910.

Application filed March 20, 1908. Serial No. 422,216.

To all whom it may concern:

Be it known that I, JOHN DESMOND, a citizen of the United States, and a resident of Chicago, county of Cook, and State of Illinois, have invented certain new and useful Improvements in Compression-Testers for Explosive-Engines, of which the following is a specification.

The invention relates to testing devices for explosive engines and seeks to provide a simple and effective device for testing the compression effected in the cylinder or cylinders of an explosive engine.

Automobiles and the like are usually provided with explosive motors having a number of cylinders, frequently as high as four and six cylinders being used. With such multiple cylinder engines, it is frequently desirable to ascertain whether or not all the cylinders are operating properly. Moreover, when the engine is not running with good efficiency, the trouble may be known to be due to leaky pistons or leaky valves, but it is frequently impossible to tell in which one or more of the several cylinders the valves or pistons are leaking and it becomes necessary to fix all of the pistons and valves, in order to be sure that the difficulty is remedied.

The present invention provides a simple and effective compression tester which may be readily attached to the different cylinders of the engine, and the amount of compression effected thereby ascertained by rotating the engine shaft. If one or more of the several cylinders do not give the proper amount of compression the trouble is immediately and quickly located.

The invention consists in the features of construction, combinations and arrangements of parts hereinafter set forth, illustrated in the accompanying drawings and more particularly pointed out in the appended claims.

In the drawings, Figure 1 is a sectional view of the multiple cylinder engine with the improved tester applied thereto. Fig. 2 is a vertical longitudinal section of the compression tester. Fig. 3 is a partial view in elevation of the same.

The form of multiple cylinder engine shown in Fig. 1 comprises two upright cylinders 10 mounted upon the crank casing 11. Pistons 12 in the cylinders are connected by pitmen rods 13 to cranks 14 upon the engine shaft 15, that is journaled in the

walls of the crank casing. Each cylinder is provided with an inlet valve 16 and an exhaust valve 17 and also with a threaded opening 18 adapted to receive a suitable ignition plug. The ignition plug 19, having 60 sparking electrodes 20 and 21, is removably screw threaded within the opening 18, as shown in the left hand cylinder in Fig. 1, so that it may be readily removed for cleaning the electrodes and for repairs. The improved compression tester is provided with a threaded nipple 22 having a reduced, threaded lower end 23, which is of standard size and adapted to removably fit within the ignition-plug opening 18 of the cylinder. 65 In this way, the ignition plug of a cylinder may be removed and the compression tester readily and conveniently placed in position.

The nipple 22 of the tester is preferably formed of steel, so that it will not readily 70 become damaged by careless handling, but in order to provide a tight fitting valve seat, a hollow brass plug 24 is snugly fitted within the bore of the nipple. The upper portion of the bore of the nipple 22 is perfectly 75 enlarged and is screw threaded as shown and the hollow plug 24 is similarly provided with an enlarged screw threaded upper end. The plug 24 is provided at its upper end with a valve seat 25, upon which a conical 80 valve 26 is snugly fitted. The valve is provided with a guide 27 which depends within the bore of the plug 24, and, at its upper end, the valve has a projecting flange or shoulder 28, which fits within a correspondingly shaped rabbet 29 in the upper end of the plug. When the valve is lifted from its seat by pressure within the cylinder, the shoulder 28 increases the area upon which 85 the escaping gases act and thus insures that 90 the valve will be lifted to afford relief of the gases.

The main body of the testing device consists of a sleeve-like casing 30 which is threaded within the outer end of the nipple 100 22 above the plug 24. The lower end of this sleeve is cut away or enlarged, as at 31, so that the valve 26 may lift freely from its seat, but preferably the bore of the sleeve is slightly smaller than the valve, so that the 105 latter cannot drop out of the casing and become injured or lost.

A valve stem 32 arranged within the sleeve-like casing 30 is provided at its lower end with a conical head 33, which fits a simi- 110

larly shaped, central depression upon the upper face of the valve. A thimble 34 threaded over the upper end of the sleeve or casing 30, is provided at its upper end 5 with a hollow projection 35, and the upper end of the valve stem 32 extends into the bore 36 of the projection 35 and is guided and held in central position thereby. A spring 37 coiled about the stem bears at its 10 ends upon the conical head 33 of the stem and upon the end wall of the thimble 34. The sleeve or casing 36 is provided at its upper end with a reduced, externally threaded portion 38, which engages the internal 15 threads of the thimble 34. Below the threads of the thimble, its bore is enlarged and unthreaded and this lower end portion 39 of the thimble 34 fits over the main body of the sleeve 30. By adjusting the thimble 34 upon 20 the casing 30, the spring 37 may be compressed to a greater or less extent, so as to vary the pressure necessary to lift the valve 26 from its seat. The lower edge portion 39 of the thimble is provided with scale marks 25 40, and the main body of the sleeve or casing 30 is provided with coöperating scale marks 41, which constitute a vernier scale to indicate accurately, the pressure of the spring 37, or rather to indicate accurately the pressure 30 in pounds per square inch, necessary to lift the valve from its seat in the different 35 adjustments of the thimble 34. At its end and on opposite sides of the projection 35, the thimble 34 is provided with escape ports 42, and an indicating device in the form of a disk 43 is loosely mounted upon the projection 35, and normally closes the ports. To prevent the removal and loss of the indicating disk 43, the upper end of the projection 40 35 is enlarged as shown.

In using the device, one of the ignition plugs of the cylinder is removed and the tester placed in position, as shown in connection with the right hand cylinder in Fig. 45 1. The engine shaft is then rotated so that a charge of air, or of air and gas will be drawn into the cylinder and compressed. As the air is compressed it will lift the valve 26 from its seat and will also cause the indicating disk 43 to move up and down. The thimble 34 is then screwed down slowly to increase the pressure of the spring 37, until the point is reached where the compression effected in the cylinder is just insufficient to raise the valve 26. This point will be clearly indicated when the disk 43 fails to move from position upon the upper end of the sleeve 34. Then by reading the vernier scale between the lower end of the sleeve 34 and 50 the main body of the casing 30, the maximum pressure effected by the cylinder may be ascertained. If this compression is the desired normal compression for the cylinder, it will indicate that the piston packings and 60 the valves of the cylinder are in proper con-

dition. If such is not the case, the maximum pressure attained will, of course, be below the desired normal. By thus testing the various cylinders of the motor, the trouble, if any exists, may be quickly located and much time and expense saved in fixing the piston packing rings and the valves. 70

It is obvious that changes may be made in the details set forth without departure from the essentials of the invention. 75

Having described my invention what I claim as new and desire to secure by Letters Patent, is:

1. A compression tester for explosive engines comprising a sleeve-like casing, a relief valve seated in said casing, a spring for holding said valve to its seat and a thimble adjustably screw threaded upon the end of said casing and adapted to bear upon the end of said spring to adjust the pressure thereof, said thimble having escape ports and said casing having a scale with which said thimble coöperates to indicate the pressure of said spring, substantially as described. 90

2. A compression tester comprising a sleeve-like casing having a reduced upper end portion, a valve seated in said casing, a spring in said casing for holding said valve to its seat, a thimble adjustably threaded upon the reduced upper end of said casing and having an unthreaded lower portion fitting over the body portion of said sleeve-like casing, said thimble having escape ports and adapted to bear upon the upper end of said spring to vary the pressure thereof and a vernier scale upon said casing and upon the lower end of said thimble, substantially as described. 95

3. A compression tester comprising a sleeve-like casing having a threaded nipple for engaging a suitable opening in the engine cylinder, a relief valve seated in said casing, a spring in said casing for holding said valve to its seat, a thimble adjustably threaded upon the upper reduced end of said casing and having an unthreaded lower end portion fitting over the main body thereof, said thimble having relief ports and adapted to bear upon the upper end of said spring to vary the pressure thereof and a scale upon said casing with which the lower edge of said casing coöperates to indicate the pressure of said spring, substantially as described. 110 115

4. A compression tester for explosive engines comprising a screw threaded nipple adapted to engage a suitable opening in the engine cylinder, a relief valve in said casing, a spring in said casing for holding said valve to its seat, a thimble adjustably threaded upon the end of said casing and bearing upon said spring to vary the pressure thereof, said casing having a scale with which said thimble coöperates to indicate the pres- 120 125 130

sure of said spring and said thimble having relief ports in its end and an indicating device loosely mounted on said thimble over said relief ports, substantially as described.

5 5. A compression tester for explosive engines comprising a casing having a screw threaded nipple adapted to engage a suitable opening in the engine cylinder, a relief valve in said casing, a coiled spring in said 10 casing for holding said valve to its seat, a sleeve adjustably threaded upon the end of said casing and adapted to bear upon said spring to vary the pressure thereof, said casing having a scale with which said thimble 15 cooperates to indicate the pressure of said spring, said thimble having a projection and relief ports on its end and an indicating disk loosely secured in position upon said projection and normally closing said ports, 20 substantially as described.

6. A compression tester comprising a screw threaded thimble adapted to engage a suitable opening in the engine cylinder, a relief valve seated in the lower end of said 25 casing and having a depending guide, a valve stem having a conical head engaging the upper face of said valve, a spring coiled about said stem and engaging said head, and a sleeve adjustably threaded upon the upper 30 end of said casing and adapted to engage the end of said spring to vary the pressure thereof, said thimble having a guide for the upper end of said valve stem and said casing

having a scale with which said thimble cooperates to indicate the pressure of said 35 spring, substantially as described.

7. A compression tester for explosive engines comprising a threaded nipple adapted to engage a suitable opening in the engine cylinder, a plug threaded in said nipple and having a valve seat at its upper end, a relief valve on said seat having guide flanges depending into the bore of said plug, a sleeve threaded at its lower end into said nipple and engaging a seat at the upper end of said 45 plug, a stem within said sleeve having a conical lower end engaging a depression in the upper face of said valve, a spring coiled about said stem and engaging said head, a thimble threaded upon the upper end of said 50 sleeve and adapted to engage the upper end of said spring to vary the pressure thereof, said thimble having a hollow projection at its upper end within which the upper end of said valve stem is guided and having relief 55 ports adjacent said projection and an indicating device loosely secured in position upon said projection and normally closing said ports, said sleeve having a scale with which the lower edge of said thimble cooperates to indicate the pressure of said 60 spring, substantially as described.
